United States Patent Office

3078-2
Des. 185,220
Patented May 19, 1959

185,220

FAMILY ALTAR OR SIMILAR ARTICLE

Boles Liubauskas, Du Bois, Pa.

Application April 21, 1958, Serial No. 50,561

Term of patent 14 years

(Cl. D29—23)

Fig 1

Fig 2

Figure 1 is a front perspective view of a family altar showing by new design; and

Figure 2 is a side perspective view of the family altar shown in Figure 1.

I claim:

The ornamental design for a family altar or similar article, as shown.

References Cited in the file of this patent

UNITED STATES PATENTS

D. 174,953	Gustafson -----	June 14, 1955
D. 181,300	Liubauskas -----	Oct. 29, 1957

OTHER REFERENCES

Ecclesiastical Art Productions, Catalog No. 30, July 1951, page 14, item No. 1699, Lord's Supper Relief.

Benziger Brothers Religious Articles Catalog, © 1936, inside of back cover, item No. 7.